UNITED STATES PATENT OFFICE

2,654,213

UNIVERSAL WATCH SETTER

Fritz Galley, Le Locle, Switzerland, assignor to
 Fabrique d'Horlogerie CHS Tissot & Fils S. A.,
 Le Locle, Switzerland, a firm of Switzerland

Application May 9, 1951, Serial No. 225,394
 In Switzerland May 12, 1950

1 Claim. (Cl. 58—43)

1

My invention has for its object a universal watch including on one hand time-indicating members and on the other hand a rotary dial controlled by the clockwork and indicating universal time in register with a stationary dial.

This watch is characterized by means for manually shifting said rotary dial independently of the above mentioned indicator members, the watch being designed so as to allow an adjustment of the rotary dial.

I have illustrated by way of example and by no means in a binding sense, three preferred embodiments of the objects of my invention in accompanying drawings, wherein:

Figs. 1, 3 and 5 are plan views respectively of each of said embodiments, certain portions of which are torn off.

Fig. 2 is a cross-section through line II—II of Fig. 1.

Fig. 4 is a cross-section through line IV—IV of Fig. 3.

Fig. 6 is a cross-section through line VI—VI of Fig. 5.

In Figs. 1 and 2, the watch illustrated carries hands 1, 2 and 3 for indicating respectively hours, minutes and seconds. The stationary dial shown at 4 and carrying the indication of hours at its periphery is annular. A dial 6 is revolvably mounted inside and coaxially with the dial 4. Said rotary dial carries the names of various large cities, symbolizing different time-belts, at its periphery and it is intended to give out universal time on a 24-hour scale 8 carried by the cooperating inner periphery of the stationary dial 4. It is possible, just as well, to provide this 24-hour scale 8 on the rotary dial 6 and the names of the different large cities 7 on the stationary dial 4. The drive of the dial 6 under the action of the clockwork is provided by a wheel 9 meshing with an our wheel shown at 10 and driving through the agency of a friction coupling a ratchet wheel 11 rigid with a wheel 12 and this latter wheel drives a toothed ring 13 fitted over an embossment 6a of the dial 6. Friction between the wheels 9 and 11 is ensured by a coil spring 14. The ratio of the gearing between the different wheels and pinions of the gearwork driving the rotary dial 6 is such that said dial executes one revolution per 24 hours.

The watch illustrated includes a hand-operable resetting device for the dial 6. This resetting arrangement includes a pusher 15 pivotally secured at 16 and the outer end 15a of which acts on a lever 17, the nose-shaped end 17a of which is adapted to cooperate with the ratchet

2

wheel 11. Spring blades 18 and 19 serve for returning the pusher 15 and the lever 17 respectively back into their inoperative positions. The operation of the pusher 15 produces thus an angular shifting of the dial 6 and said shifting is not transmitted to the other indicating parts by reason of the frictional engagement between the wheels 9 and 11.

The setting of the hands of said watch is performed in two different manners:

When the time belt remains the same and it is merely desired to set the watch right after a stoppage or an irregular working of the watch, the person wearing the watch acts on the button shown at 20 so as to produce an angular shifting of the hands 1 and 2 and also of the dial 6. If, in contradistinction, the time-setting is required on account of a change in the time belt, it is necessary to move the button 20 in order to set the hands 1 and 2 by the time of the further time belt in which the wearer of the watch enters. But this time setting shifts the dial 6 which should not in this case move with the hands. The wearer of the watch acts then on the pusher 15 so as to return the dial 6 into the position it was occupying at the moment considered and that should not have been modified.

In the second embodiment illustrated in Figs. 3 and 4, the stationary dial 21 carrying the scales of 12 and 24 hours is located centrally and inside the rotary dial shown at 22 which is annular and carries the names of the large reference cities. Said dial is rigid with a toothed ring 23 meshing with a pinion 24 rigid with a ratchet wheel 25. The wheel 25 is driven in its turn by a similar wheel 26 rigid with a pinion 27. The pinion 27 is driven by intermediate wheels illustrated at 28 through the agency of an intermediate pinion 29. The dial 22 executes one revolution per 24 hours. The two wheels 25 and 26 forming a catch system are adapted to cooperate with one another through the agency of a spring blade 30 shown in Fig. 3. The resetting arrangement of the dial 22 includes a pusher 31 controlling a catch 32 cooperating with the pinion 24. The position of the series of names of large cities and of the annular 24-hour scale may also be interchanged as precedingly.

In the last embodiment illustrated in Figs. 5 and 6, the rotary dial is constituted by an annular dial designated by 33 and carrying a 24-hour scale. Said rotary dial is located between an inner stationary dial 34 carrying an annular 12-hour scale and an outer annular stationary

dial 35 carrying the names of the large reference cities. The annular dial 33 is rigid with a toothed ring 36 that is controlled by the hour wheel 37 through the agency of a gear work including a ratchet wheel. A dial-resetting arrangement similar to that already described allows shifting the annular dial 33 independently of the indicator hands.

In a modification, the manual shifting of the rotary dial may be performed by means of a ring replacing the pusher means or even by means of a rotary bezel.

What I claim is:

In a watch, the combination of time-indicating parts, a clockwork, a transmission operatively connecting the clockwork with said parts, a stationary dial cooperating with said parts, a rotary dial coaxial with the stationary dial, means controlled by the transmission for driving the rotary dial including a shiftable member adapted to be shifted with reference to the transmission to allow correction of the angular setting of the rotary dial, hand operable means

including an arc-shaped pusher extending on more than 180° and provided with an extension intended to be manually operated, a lever arranged to simultaneously effect a movement of translation and of rotation, said lever being controlled by said pusher and one end of which being adapted to operatively engage the shiftable member and thus set the rotary dial and two registering annular scales carried respectively by the cooperating peripheries of the two dials and including respectively a subdivision in hours and a subdivision in time belts.

FRITZ GALLEY.
